UNITED STATES PATENT OFFICE

ERICH H. LICHTENBERG, OF MILWAUKEE, WISCONSIN, ASSIGNOR TO KOEHRING COMPANY, OF MILWAUKEE, WISCONSIN, A CORPORATION

BOOM-HOIST SAFETY MEANS

Application filed March 17, 1927. Serial No. 176,087.

This invention relates to improvements in cranes of the boom hoist type and has for its primary object the prevention of overload on the beam and also prevention of back-swinging when peaked up.

With these and other objects in view, as will in part hereinafter become apparent and in part be stated, the invention comprises an automatic control for effecting cessation of movement of the parts either from overload or from movement beyond the plane of safety.

The invention in greater detail includes means for automatically discontinuing delivery of power under any such unfavorable conditions.

The invention also comprises certain other novel constructions, combinations and arrangements of parts as will be subsequently specified and claimed.

20 In the accompanying drawings,

Fig. 1 is a view in side elevation of a crane equipped with an illustrative embodiment of the present invention, the boom being seen in operative position in full lines and peaked up in dotted lines.

Fig. 2 is a fragmentary plan on enlarged scale of the dead end anchorage of the hoist cable.

Fig. 3 is a longitudinal, vertical section taken approximately on the planes indicated by line 3—3 of Fig. 2, looking in the direction indicated by the arrows, parts being seen in elevation.

Fig. 4 is a transverse, vertical section taken on plane indicated by line 4—4 of Fig. 2, looking in the direction indicated by the arrows.

Figure 5 is an enlarged plan view, showing the spring contact construction in detail.

In crane construction, it is common practice to mount the crane car body as far at one side of the axis of its support as practicable, so that its weight and the weight of its contained machinery may serve as a counter-balance for the boom and load sustained thereby. Care must be accordingly exercised to prevent toppling forward under an excessive load on the boom and to prevent toppling rearward by peaking the boom up too high, that is causing it to approach too

nearly an upstanding position where its weight is liable to be added to the weight of the crane car body instead of balanced against it. It is an essential object of the present invention to overcome the danger of either of these possible exigencies, and the invention is, of course, applicable to practically any type of crane and especially any type with the counter-balancing body mounting, one embodiment of the invention being illustratively disclosed in the accompanying drawing, in which 1 is the crane car body rotatively mounted on the multi-plane tractor 2 and arranged off center with respect to its support. A hoist boom 3 is pivotally connected, as usual, to the crane body but at the opposite side of the center of support from the major portion of car body 1. Anchored to the top of car body 1, and extending to the outer end of boom 3, as usual, is the cable 4, carrying the clam shell or other scoop, bucket or load carrier 5.

The anchorage of the dead end of cable 4 is of special construction and seen in detail in Figs. 2, 3 and 4. This special construction includes a yoke 6, pivoted to an eye 6' by a through bolt 6'', said eye 6' extending from an appropriate yoke 9, bolted or otherwise suitably connected to an appropriate part of the upper portion of crane body 1. The bight of yoke 6 is connected to or integrally carries a preferably elongated loop 7, interlinked in a similarly elongated loop 8, which last named loop terminates in an inwardly flaring sleeve 10, in which the cable 4 is effectively anchored. A guide band 11 is formed integral with or appropriately connected to loop 7 and is arranged substantially transversely thereof to encircle and slide along the loop 8. A compression spring 12 is arranged with in the loops 7 and 8 and interposed between the opposing ends of said loops, so that when outward longitudinal stress is exerted on loop 8 it compresses spring 12 against the interlinked end of loop 7. The band 11 serves effectively to guide the loops in their relative movements and also to restrain against such lateral play of the loops with respect to each other as might enable dislocation of spring 12. Band 11 is also employed as a

contact carrier, although any other part of the loop 7 might be utilized for this purpose.

A contact plate 13 is fixed to one side of band 11 and insulated therefrom by an insulating sheet or block 14 and secured thereto by a bolt or other appropriate fastening means 15. Electrical conductor contacts 15, 16 and 17 are also preferably clamped by the bolt 15^a, so as to be in electrical contact with each other and with the plate 13. An insulating sleeve 17^a is preferably provided for the bolt 15^a to prevent short-circuiting of the parts 13, 16 and 17 with band 11. An outstanding lug 18 projects from the side of the loop 8 in the path of movement of the projecting end of plate 13, in position to be contacted by said plate when spring 12 is compressed under sufficient load to occasion the requisite travel of the band 11 to effect this result, such travel occurring only under excessive load.

Hoist mechanism and a motor for driving the same, such as an ordinary internal combustion engine, are, of course, mounted within crane car body 1 and may be of any of the well-known types in use. The power source, whether an internal combustion engine or otherwise, depends for continuity of its operation on current supplied through the leads 17 and 16, the lead 17, in the case of an internal combustion engine, extending from the magneto, spark coil or other source of current, and the lead 16 extending to the timer or distributor of the engine. The magneto or other source of current is, of course, grounded on the frame of the machine. It follows therefore that whenever an over-balancing or other excess load is picked up by the clam shell or other load carrier 5, the resilient anchorage of the cable 4 will cause the cable to move longitudinally to an extent, causing the loop 8 to move relative to the loop 7 sufficiently for bringing the lug 18 into contact with the plate 13. When this occurs the current supplied through the lead 17 no longer follows the lead 16 alone, but is divided between the two leads 16 and 17, the major portion of the current taking the path of less resistance through the plate 13, lug 18, and connected parts to the ground connection of the magneto or other source of current. The motor is thereby short-circuited and delivery of power discontinued.

Extending from a point in contact with the plate 13, preferably by being interposed between the contact of leads 16 and 17 and plate 13, is an electrical conductor or lead 19 arranged to extend along the cable 4, being preferably sustained in position along the cable by appropriate clips 20, 20, engaging the cable 4 and engaging, but insulated from, the conductor of lead 19.

Well up the cable 4 and at such a height in the length of the cable as to effect the results desired at the required time to prevent

the boom 3 from being raised too near a vertical position, that is from being picked up too high, the lead 19 is provided with a loose end portion 21, having an exposed contactor end located to contact with the boom 3, when the boom is sufficiently elevated, as seen in dotted lines of Fig. 1. Hence, before the boom reaches a point of dangerous elevation, the boom will strike the exposed end of the projecting portion 21 of lead 20 and thereby close the circuit from the source of current through leads 17 and 19 to ground, and cessation of the operation of the motor will be thus effected to prevent further elevation of the boom.

It is to be noted that while the connections shown and described are especially well adapted for use in controlling the operation of an internal combustion engine, the shunting of the circuit incident to contact produced by excessive movement of one or the other parts involved, whereby a dangerous condition is avoided, is also well adapted for adaptation to motors of other types, so long as electric current is utilized as a controlling factor in the operation of such motors.

What is claimed is:

In combination, a crane comprising a body, a boom for supporting loads from the body and adapted to be peaked, an operating cable connected with the boom for effecting elevation of the boom and load, said operating cable including a coupling, an electric circuit contact device mounted on said coupling, the coupling comprising relatively movable parts shiftable incident to varying loads handled by the operating cable, the coupling device having a movable part carrying a contact device cooperative with that previously mentioned, whereby to enable short circuiting of the circuit including the first mentioned contact device, other contact means associated with the operating cable and contacting with the boom and connected with the first mentioned contact means whereby to short circuit the said electrical circuit substantially as described when the boom is peaked to a point beyond safety, and an electrical circuit common to said contacts.

In testimony whereof I affix my signature. 115
